(57) **CLAIM**

I claim the ornamental design for a rectangular tridimensional piñata, substantially as shown.

DESCRIPTION

FIG. 1 is a perspective view of a rectangular tridimensional piñata showing my new design;

FIG. 2 is a front elevation view of the rectangular tridimensional piñata;

FIG. 3 is a rear elevation view, opposite that of FIG. 2, of the rectangular tridimensional piñata;

FIG. 4 is a right side elevation view of the rectangular tridimensional piñata;

FIG. 5 is a left side elevation view, opposite that of FIG. 4, of the rectangular tridimensional piñata;

FIG. 6 is a top plan view of the rectangular tridimensional piñata; and,

FIG. 7 is a bottom plan view, opposite that of FIG. 6, of the rectangular tridimensional piñata.
